STOP MOTION FOR STRANDING MACHINES

Albert E. Winslow, Mystic, Conn., assignor to Atwood Machine Company, a corporation of Connecticut

Application October 29, 1943, Serial No. 508,133

10 Claims. (Cl. 57—81)

This invention relates to a stranding machine or an apparatus for putting twist into one or laying several strands of work and is directed more particularly to the double twist type of machine wherein two twists or lays are placed in the strand for each single revolution of the flyer.

Heretofore, in the use of a machine of the above type if one of the several strands breaks the broken end may pass into a tubular spindle before the machine could be stopped and the end pieced up, which requires considerable work in rethreading the machine to pass the broken end into the hollow spindle. Because of the mountings of the creel or package carrier which substantially floats upon rotating spindle with the rotating twist imparting member located below the creel difficulty is encountered in the applying of any stop motion to a device of this character.

One of the objects of this invention is to provide in a machine of this character a stop motion which will effectively control the operation of the apparatus so that the apparatus may be stopped immediately should a break in one of the strands occur.

Another object of this invention is to provide an electrical stop motion and to conduct current to the relatively stationary floating creel in such a manner that an electrical operation may be had for stopping the mechanism.

A more specific object of this invention is an arrangement to conduct electrical energy through the rotating means which imparts twist or helically lays the strand.

With these and other objects in view, the invention consists of certain novel features of construction, as will be more fully described and particularly pointed out in the appended claims.

In the accompanying drawings:

Fig. 1 is an elevation of a portion of a machine equipped with the stop motion of my invention;

Fig. 2 is a top plan view with a large part of the operating part omitted;

Fig. 3 is a sectional view taken on substantially line 3—3 of Fig. 1, also with parts omitted;

Fig. 4 is a fragmental sectional view illustrating the relative rotating parts on a larger scale and showing the electrical connection and mounting of the parts;

Fig. 5 is a sectional view of a fragmental portion showing the electrical conducting means from the creel to the upper disc of the rotating flyer member;

Fig. 6 is a fragmental sectional detail illustrating the electrical connection between the station-

ary framework of the device and the lower disc of the rotating flyer member;

Fig. 7 is a fragmental sectional detail illustrating the electrical connection between the two discs of the rotating flyer member;

Fig. 8 is a fragmental sectional detail illustrating the electrical connection between the upper deck of the creel and the annular contact of the main deck of the creel;

Fig. 9 is a sectional view illustrating the guide posts and circuit establishing contact member which is guided thereby; also illustrating a strand of material extending about the post;

Fig. 10 is a diagrammatic view illustrating the wiring for the circuit or circuits which are utilized in the apparatus.

This invention is directed more particularly to a stop motion which forms a part of a complete cable making machine which is the subject matter of my co-pending application Ser. No. 517,859 to which reference is made for a more complete showing of the operating parts of the complete machine.

With reference to the drawings 10 designates a spindle which is driven from some source of power such for instance as an electric motor 11 by means of a belt extending about the pulley of the motor and about the pulley 12 fixedly secured upon the spindle 10. The spindle is suitably rotatably mounted in a casing 13 or framework which is a stationary part of the machine.

A creel support 14 has a hub 15 which is rotatably supported upon a spindle in spaced relation to the framework or casing 13 of the machine. A rotary flyer member designated generally 16 is fixed to the spindle to rotate therewith and consists of a hub portion 17 with discs 18 and 19 secured thereto for rotation therewith. Shafts 20 are rotatably mounted in sleeves 20' which are rotatably mounted in the discs 18 and 19 each of which carries pulleys 21 at the lower end and 22 at the upper end of the shaft 20. A belt connection 23 embraces pulley 21 and the stationary hub 24 so as to drive the shafts 20 upon each rotation of the spindle. A belt 25 embraces pulley 22 and the hub 26 which is fixed on creel support 14 so that as the shaft 20 revolves the drive will tend to move the creel 14 in the opposite direction. It will thus be apparent that although the spindle revolves the shafts 20 they will reversely drive the creel 14 so as to maintain the creel in the same relative position to the stationary frame thus the creel 14 will have no rotation relative to the casing 13 and will remain stationary.

The package support 14 has spindles 30 extending upwardly therefrom, there being shown six of such spindles in the illustration herein. Each of these spindles retains a package 31 mounted thereon by means of the wing nut 32. The strand of wire on such package 31 extends from the package about the guide post designated generally 33 as shown at 34 in Fig. 3, thence over the guide sheave 35 and about the drums 36 and 37 a plurality number of times and then over the guide sheaves 38 and 39 and into the hollow spindle 10.

Certain of the guides designated generally 33 are utilized for supporting of the upper deck 40 upon which spindle 41 is mounted for the reception of a package 42 of strand material which is held in position by the wing nut 43. A guide post designated generally 44 (see Fig. 2) is mounted upon this upper deck 40 while strand material 45 may extend from the package 42 about this guide 44 and thence to a sheave 46, about the drums 47 and 48 and thence over another sheave 49 and second shift 50 to extend through the hollow spindle 10 and serve as a core about which the cable is to be formed.

The cable designated 51 emerges from the spindle over a guide sheave 52 and thence extends about a guide sheave 53 which is rotatably mounted near the periphery of the disc 48, thence this cable 51 extends upwardly over suitable guides to some packaging means, such for instance as is more fully explained in my co-pending application above referred to. The portion of the cable extending upwardly from the sheave 53 as it revolves follows substantially the surface of a cone which would completely embrace the creel thus making it impossible to extend any wire or part to the creel laterally of the spindle along the vertical extent of the work loop.

Each of the guide posts 33 (see Fig. 9) consists of a solid upstanding member 55 which is threaded as at 56 into the creel support 14. A bearing 57 is provided on this member 55 which is held in position by a spring ring 58, a similar bearing is provided near the upper end of the member, and a sleeve 59 is rotatably supported on these bearings which may freely rotate as the strand designated 34 is drawn about this guide post. A collar or circuit closing member 60 is slidably related to the sleeve 59 and will move by gravity to the lower part of the sleeve when free to do so. This collar has an outwardly rounded flange 61 to rest upon the strand material 34 so as to be supported thereby and prevented from gravitating to its lower position so long as the strand material extends about the post. However, when this strand material breaks the collar will slide to its lowermost position.

An annular electrical contact strip 63 is supported by insulation 64 from the creel 14 and is provided with openings 65 sufficient so as to space the contact strip from each of the guide posts which extend therethrough. An electrical connection may be made between the strip 63 and post by the collar when in its lowermost position.

The post 44 is similar to the post 33 but is mounted on the upper deck 40 by the portion 56 thereof to be threaded into the deck 40 through an insulation bushing 65 (see Fig. 8) which is shouldered as at 66 to support the arm 67 which extends therefrom in spaced relation to the deck. This arm 67 is thus insulatingly supported with reference to the post which has connection with the structural work of the machine. A similar

sleeve or collar 60 is carried by this post 44 and may bridge the conducting arm 67 and the post for establishing an electrical connection between them. The arm 67 is electrically connected to the annular member 63 by a rod 68 extending through the opening 69 in the deck 40 to insulate it therefrom and extending into a sleeve 70 which is electrically connected to the annular contact member 63.

The flange 72 of the creel is equipped with a boss 73 having a bore 74 (see Fig. 5) in which the insulating sleeve 75 is mounted. This sleeve carries a brush 76 pressed by the spring 77 which may be adjusted by the threaded rod 78 that the desired pressure may be obtained and which rod is held in position by threadingly engaging a part of the bushing. Electrical connection is established between the brush 76 and the annular contact 63 by a strip 79 secured as at 80 to the member 63 and by nut 81 to the threaded rod 78 to establish electrical connection between them.

The brush 76 engages an annular contact member 83 which is insulated as at 84 from the disk 18 but so located that as the disk revolves this annular member will be engaged by the brush 76 at all times. An annular member 85 carried on the under side of the disk 19 (see Fig. 7) is electrically connected to the annular member 83 by a strap 84 secured to these members by bolts 86 and 87 through insulating bushings 88 in both of said disks such as by means of nuts 89.

The framework 13 is also equipped with a boss 90 (see Fig. 6) having a bore 91 with insulating bushings 92 therein which holds a threaded member 93 to adjustably engage the spring 94 which urges the brush 95 against the annular contact member 85. A certain terminal arrangement by nuts 96 and 97 enable the circuit lead 98 to be secured thereto.

The electrical circuit which is involved in this mechanism consists of power supplied through lines 100 and 101 to the electrical motor 11 and through the control 102 providing terminals to be closed by the switch 103. This switch is normally closed but may be opened by means of a solenoid 104 in a circuit consisting of an energizing source 105 with terminals 106 and 107, one of which represents the annular contact 63 while the other represents the ground of the machine, both of which may be bridged by the collar designated generally 60 which spans these two points in completing the circuit in the machine.

From the source of energy 105 the live contact 63 or 67 as represented at 106 is energized through the insulated connections traced by 98, 93, 94, 95, 85, 86, 83, 76, 71, 78, 79, 63 and 70, 68 to 67. The ground or return circuit is through the frame of the machine.

I claim:

1. In a strand handling machine, a vertically disposed rotating spindle, a package support mounted thereon and differentially driven from the spindle to remain stationary, a member rotating with the spindle below said package support, and means including an annular strip on one part and brush on the other engaging therewith to transfer electrical energy to said package support.

2. In a strand handling machine, a rotating vertically disposed spindle, a package support mounted thereon and differentially driven from the spindle to remain substantially stationary, a member rotating with the spindle below said package support to revolve the strand about the package support, and means including an annular

strip on one part and brush on the other engaging therewith to transfer electrical energy to said package support through said rotating member.

3. In a strand handling machine having a stationary frame, a vertically disposed rotating spindle in said frame, a package support mounted thereon and differentially driven from the spindle to remain substantially stationary, a member rotating with the spindle below said package support to revolve the strand about the package support, and means including an annular strip on said rotating member and brushes on said package support contacting with said strip to transfer electrical energy to said package support through said rotary member.

4. In a strand handling machine, a vertically disposed rotating spindle, a package support mounted thereon and differentially driven from the spindle to remain stationary, a member rotating with the spindle below said package support, and means including an annular strip on one part and brush on the other engaging therewith to transfer electrical energy to said package support, a package on said support and means controlled by the strand from said package to close an electrical circuit including said transfer means.

5. In a strand handling machine, a vertically disposed rotating spindle, a package support mounted thereon and differentially driven from the spindle to remain stationary, a member rotating with the spindle below said package support, and means including an annular strip on one part and brush on the other engaging therewith to transfer electrical energy to said package support, packages on said support and means including a unit controlled by each package to close an electrical circuit including said transfer means.

6. In a strand handling machine having a stationary frame, a vertically disposed rotating spindle mounted on said frame, a package support mounted on said spindle and differentially driven from the spindle to remain substantially stationary, a member rotating with the spindle below said package support to revolve the strand about the package support, and means including annular strips on said rotating member and brushes on said stationary frame and package support contacting with said annular strips to transfer electrical energy to said package support through said rotary member, a package on said support and means controlled by the strand from said package to close an electrical circuit including said strips and brushes.

7. In a strand handling machine having a stationary frame, a vertically disposed rotating

spindle on said frame, a package support mounted on said spindle and differentially driven from the spindle to remain substantially stationary, a member rotating with the spindle below said package support to revolve the strand about the package support, and means including annular strips on said rotating member and brushes on said stationary frame and package support contacting with said strips to transfer electrical energy to said package support through said rotary member, packages on said support and means including a unit controlled by each package to close an electrical circuit including said strips and brushes.

15. 8. In a strand handling machine, a rotating spindle, a package support mounted thereon and differentially driven from the spindle to remain stationary, a member rotating with the spindle below said package support, and means including an annular strip on one part and brush on the other engaging therewith to transfer electrical energy to said package support, a package on said support and means controlled by the strand from said package to close an electrical circuit including said transfer means, said control means including a guide for the strand and a member slidable along the guide and held out of electrical contact by said strand.

9. In a strand handling machine, a rotating spindle, a package support mounted thereon and differentially driven from the spindle to remain stationary, a member rotating with the spindle below said package support, and means including an annular strip on one part and brush on the other engaging therewith to transfer electrical energy to said package support, packages on said support and means including a unit controlled by each package to close an electrical circuit including said transfer means, said control means including a guide for each strand and a member slidable along each guide and held out of electrical contact by each strand.

10. In a strand handling machine, a support, a package of strand material thereon, means for drawing the strand from said package including a revolving member, an electrical stop motion comprising a live contact, a guide, a circuit closing member movable along said guide to engage said contact and held away from said contact by the strand of material extending from said package about said guide, annular contact strip and brush means between said package support and revolving member for energizing said live contact and means having an electric circuit including said live contact to stop the machine when the circuit is closed.

ALBERT E. WINSLOW.
